JOSEPH SUNNEN, OF ST. LOUIS, MISSOURI

SPLIT-LOCK CATCHER

Application filed July 8, 1929. Serial No. 376,572.

This invention relates generally to tools for internal combustion engines, and more particularly to catchers for catching split locks of the valve assembly.

As is well known in the art, the lower end of each valve spring is seated on a retaining washer which is held on the valve stem by means of a suitable lock. Generally this lock consists of a member split longitudinally in two halves and having its outer face tapering upwardly to fit into a similarly shaped recess formed in the underside of said retaining washer. The valve stem is provided with a peripheral groove in which said lock is seated and forms a support for the washer. The two halves of the lock are held together by the recessed portion of said washer and the valve spring, the lower end of which presses against said washer and holds it against said lock.

Now it is frequently necessary to dismantle the valve assembly, as, for instance, in grinding valves or in making repairs. During this operation the valve spring has to be compressed against the upper stationary end (preferably by a suitable valve lifter) in order to release said lock, whereupon the valve can be removed from the block. The valve spring can then be also removed.

When compressing the spring, as soon as the washer is moved away from the lock members, the latter have a tendency to become disengaged from the valve stem and drop into the crank case. This also happens when releasing the spring in position. As the space in which the parts are located is very limited and is usually so located as to be almost inaccessible, considerable time is lost in dismantling and replacing the valve assembly. This is particularly true of certain makes of automobile engines which are some of the hardest jobs to work out.

When the lock members which are of comparatively small size drop into the crank case, they are hard to find and to retrieve so that considerable time is lost on account of the dropping of the lock members.

It is the primary object of the present invention to provide a suitable split lock catcher which can be readily placed in position in

the engine block surrounding the valve stem so as to catch said split locks as soon as they are released without in any way interfering with the removal and replacement of the valve spring or the operation of the valve lifter when used for this purpose. 55

Other objects of the invention are to provide a split lock catcher which will fit in position in various makes of engines and which is efficient in performing its intended function and can be economically manufactured. 60

With these and other objects in view, my invention consists in certain novel features of construction and arrangement of parts, hereinafter more fully described and claimed, 65 and illustrated in the accompanying drawings, in which—

Figure 1 is a front elevational view of a portion of the cylinder block showing the catcher in position therein.

Figure 2 is a vertical cross section taken on line 2—2 of Figure 1 with the spring and washer shown in dotted lines.

Figure 3 is a side elevational view of the catcher.

Figure 4 is a horizontal cross section 75 through the same.

The invention consists of a cup-shaped member 10 open on one side as indicated at 11. This cup-shaped member has a vertically disposed side wall 12 and a bottom 14. The side wall 12 includes a semi-circular portion 15 and straight parallel portions 16 which extend forwardly from said circular portion 15 and form the opening 11. The arcuate portion 15 is formed with a horizontally disposed slot 17 arranged substantially intermediate the top and bottom of said side wall, there being a lower slot 18 arranged adjacent to the bottom 14 and somewhat shorter than the upper slot 17. That portion of the wall 15 arranged above slot 17 is cut into two halves 19 and 20 by a vertical slot which terminates in slot 17. Thus, there is left only a comparatively narrow band 21 uniting the two opposite halves of the side wall 12 which provides sufficient resiliency to enable the catcher to slip in position on the tappet. 90

The bottom 14 is formed by a pair of ex- 100

tensions 22, each of which is formed integral with the corresponding half of wall 12 and is bent inwardly and horizontally. The edges of these extensions are formed with co-operating substantially semi-circular notches 24 which are of sufficient size to receive there-between the tappet A of the valve assembly. The forward ends of the edges of these extensions are formed so as to provide an outwardly flared mouth 25 which facilitates the positioning of the catcher on said tappet. Extensions 22 are provided with rearward projections 26, portions of which are bent at right angles so as to provide a suitable hand-hold 27.

In using the device, the catcher is inserted into the valve assembly pocket formed in the cylinder block with the open end of the catcher presented inwardly so as to allow the split bottom 14 to engage the tappet A. When the catcher is in position, it is given a half turn so as to present the open end thereof outwardly and permit access to the valve assembly. With the catcher thus positioned, a valve lifter may now be used to engage the retaining washer C and move it and the lower end of the spring upwardly, thereby exposing split lock members D. When these lock members drop from the valve stem, they are retained by the catcher from which they can be easily removed.

The catcher is so constructed that it surrounds the lower end of the valve spring and the valve stem without however interfering with the assembly and disassembly thereof. The bottom 14 of the catcher is formed so as to enclose completely the tappet and prevent the split lock from dropping into the crank case. The slots or cuts formed in the arcuate portion of the wall of the catcher increase the flexibility thereof so it may be easily placed in position and at the same time provide enough resiliency to enable the forward end of the catcher to close against the tappet and hold the catcher in position therein.

The sides 19 and 20 are provided each with an aperture 28, through which may be passed a looped string or wire used for suspending the tool when not in use.

The replacer is of simple construction, is compact in size so that it will fit in restricted spaces, and can be manufactured economically.

While I have shown and described herein the preferred embodiment of my invention, it is to be understood that various changes can be made in the construction and shape of my replacer, without departing from the spirit of my invention.

I claim:

1. A split lock catcher comprising a cup-shaped member having one side open and provided with a split bottom having a split opening for receiving a valve tappet.

2. A split lock catcher comprising a cup-

shaped member having one side open and having a bottom split on a line at right angles to said open side, the opposed edges of said split bottom sections being provided with cooperating recesses opening toward said open side and adapted to receive the valve tappet so as to enclose the split locks.

3. A split lock catcher comprising a member having a split bottom and a peripheral side wall open on one side, said bottom wall being provided with an opening presented toward said open side and adapted to receive a valve tappet.

4. A split lock catcher comprising a member having a split bottom and a peripheral side wall open at one side, said bottom wall being provided with an opening presented toward said open side and adapted to receive a valve tappet.

5. As a new article of manufacture, a catcher for valve stem split locks comprising a single piece member having a side wall open on one side, and a bottom wall provided with a central aperture extending toward the open edge of said bottom, said side wall being provided with a series of cuts arranged opposite to said open side for increasing the flexibility of said member.

6. As a new article of manufacture, a catcher for valve stem split locks comprising a single piece member having a side wall open on one side, a bottom wall provided with a central aperture extending toward the open edge of said bottom, said side wall being provided with a series of cuts arranged opposite to said open side for increasing the flexibility of said member, and projections formed integral with the bottom of said member and extending rearwardly therefrom to provide a suitable hand-hold for said member.

7. A device of the class described comprising a container having a portion of its peripheral wall cut away and having a bottom wall split at right angles to said open portion, said bottom wall being provided in its opposed edges with cooperating recesses opening toward the open edge of said bottom and adapted to receive the upper end of a tappet for supporting said container in position.

8. As a new article of manufacture, a lock catcher for valve assemblies of internal combustion engines, comprising a cup-shaped member having a portion of the peripheral wall removed and provided in its bottom with a central aperture opening outwardly through the open edge of said bottom.

9. As a new article of manufacture, a catcher comprising a cup-shaped member having one side open to enable the container to be placed laterally in position to surround partially the lower part of the valve assembly and to provide access thereto through

5 said open side, the bottom of said container being provided with a central aperture opening outwardly through the open edge of said bottom, to permit positioning of said container on the upper end of the tappet of said valve assembly.

- 10 10. As a new article of manufacture, a catcher comprising a cup-shaped member having one side open to enable the container to be placed laterally in position to surround partially the lower part of the valve assembly and to provide access thereto through said open side, the bottom of said container being provided with a central aperture opening outwardly through the open edge of said bottom 15 to permit positioning of said container on the upper end of the tappet of said valve assembly, and an outward extension on said container for enabling manipulation thereof.
- 20 11. As a new article of manufacture, a cup-shaped member having one side cut away to provide access thereto and having the bottom wall cut substantially at right angles to said cut-away portion.

- 25 12. As a new article of manufacture, a cup-shaped member having one side cut away to provide access thereto and having the bottom wall provided with a central aperture to enable said member to be positioned on the 30 upper end of a tappet rod, said bottom wall being cut radially from said aperture to allow the withdrawal of said member in a lateral direction.

In testimony whereof I hereunto affix my
35 signature this 29 day of June, 1929.

JOSEPH SUNNEN.
